UNITED STATES PATENT OFFICE.

DANA H. BENJAMIN, OF CLEVELAND HEIGHTS, OHIO, ASSIGNOR TO THE AMERICAN LAUNDRY MACHINERY COMPANY, OF CINCINNATI, OHIO, A CORPORATION OF OHIO.

PRESSING AND IRONING MACHINE.

Application filed June 28, 1926. Serial No. 119,086.

This invention relates to pressing and ironing machines of the class used in laundries and more particularly to the type of such machines having power means for effecting pressure between the ironing members after they have been brought into engagement with each other by hand.

The ultimate object of the invention is to provide an efficient and powerful means for compressing the objects to be ironed between the pressing members, and at the same time to provide for safety in operation of the machine by making it impossible for the pressing power to be applied until the pressing members are in contact and therefore until the operator is safely clear of the members.

To accomplish these objects I provide a pressing machine in which the movable pressing member is closed upon its co-operating fixed member by hand and in which by the mechanism employed it is impossible for the power to be applied to the movable pressing member until it has been so positioned by hand; and since any portion of the operator's body would prevent such contact, it would be impossible to injure the operator between the pressing members. The mechanism employed includes a toggle arrangement through which the power must be applied to the pressing members, straightening of the toggle being accomplished by closing the press, the toggle being incapable of transmitting power except in such straightened position.

Further objects, details and advantages of the invention will be apparent from the following description taken in connection with the accompanying drawings in which Fig. 1 is a side elevation of a pressing machine exemplifying my invention, parts being broken away to show construction; Fig. 2 is a longitudinal section in the plane of line 2—2 of Fig. 3; Fig. 3 is a horizontal section in the plane of line 3—3, Figs. 1 and 2; Fig. 4 is a detail section in the plane of line 4—4, Fig. 3.

Referring now to Fig. 1 the principal parts of the pressing machine are the base or frame 1 upon which is fixed the padded buck 2 and movably mounted the heated ironing member 5 adapted to co-operate with the buck 2 to constitute the part of the pressing members between which articles to be pressed or ironed, are compressed. The

ironing member is carried by an arm 4 pivoted at 4^a upon the extension 1^a of the frame of the machine for movement to open or close the press.

Secured upon the arm 4 at the pivot 7^a and adjustable with the arm by means of the handle 10 on the screw 12 in the threaded web 11 of the arm, is a member 7 provided with a depending arm as shown. Upon the rear end of the arm 4 is a weight 6. It will be seen that the arm 4 carrying the ironing member 5 the counterweight 6 and the member 7 comprises a unit movable about the pivot point 4^a of the arm.

A handle 13 is provided for convenient hand operation of this unit to close the press; and to the depending arm of the member 7 is operatively secured power means for applying pressure to the ironing member in closed position of the press as will be described.

Upon the base of the press is a motor 14 connected through the coupler 17 to drive through a gear reduction indicated generally by the reference numeral 18 a shaft 19 on which is mounted a plate carrying the crank pin 20 which may be provided with a roller as shown. Pivotedly mounted at 21 is a pressure lever 22 the lower arm of which is provided with a slot in which the crank pin 20 projects so that oscillation of the lever 22 would result from continuous rotation of shaft 19. To a laterally extending arm on the lever 22 at the point 23 is connected the link 24 which in turn is connected through the pair of links 25 to the member 7 at the point 9, arrangement of the links 24 and 25 being obviously that of a toggle. Pivotedly mounted at 27 is a hook shaped member 28 provided with a cam surface 29 adapted by suitable rotation of the hook to engage an extension such as the roller 26 at the joint of the toggle referred to. A link 30 extending between the hook and the upper extremity of the lever 22 imparts motion to the hook upon movement of the lever in a manner to be described.

Operation of the linkage and mechanism referred to in connection with that of the press is as follows: Commencing with the press in open position as shown in full lines Fig. 1, after the operator has laid the article to be pressed upon the buck 2 the press is closed by grasping the handle 13 and pulling the ironing member down into contact

with the article. This moves the depending arm of the member 7 to the dot dash position shown and extends the toggle members 24 and 25 to the substantially horizontal dot dash position indicated. Should the handle 13 be now released the weight of the toggle members would break the toggle joint and owing to the balancing of the parts about the axis 4^a the press would open.

- 10 Holding the press closed, the operator by means of the handle 31 acting through suitable linkage shown, but forming no part of this invention, effects contact of switch 32 to start the motor which is arranged to cause 15 rotation of the shaft 19 in the direction indicated by the arrows, Figs. 1 and 2. This actuation of the motor will be automatically interrupted upon a rotation of shaft 19 from the position indicated in Fig. 1 to that 20 indicated in Fig. 2 by a time switch forming no part of this invention but indicated generally by the reference numeral 33. Upon initiation of this movement the hook 28 is swung to beneath the roller 26 to lock the 25 toggle joint, after which the handle 13 may be released. Continued movement of the shaft 19 with the pin 20 will cause the cam surface upon the hook to act through the roller to further straighten the toggle joint 30 and thus apply pressure to the member 7 to compress the article between the pressing members. As the lever 22 continues to move further pressure, the short rearwardly extending arm 34 of the lever 22 forming a 35 third toggle member, and with the link 24 a second toggle joint at 23.

After sufficient pressing time has elapsed, the handle 31 is moved to restart the motor 40 14 in the same direction, rotation of the motor being automatically interrupted by the timing switch 33 as before, upon return of the crank pin 20 to its original position in Fig. 1. During this rotation the hook 28 45 is removed from the toggle joint which owing to the weight and position of the links 24 and 25 is broken, allowing the press to open to its original open position.

What I claim is:

- 50 1. A pressing machine, comprising a frame, a pair of relatively movable pressing members mounted thereon, one of said members having a depending arm, an actuating member movable on said frame by power means, toggle members connecting said depending arm and said actuating member and adapted to be extended substantially horizontally by said arm as the press is closed, and means arranged to engage said toggle members to 55 support the same when moved to said extended relation, said actuating member being adapted to exert pressure upon said arm through said toggle members when so extended, to thereby effect pressure between 60 said pressing members.

2. A pressing machine, comprising a frame, a pair of relatively movable pressing members mounted thereon, one of said members having a depending arm, an actuating member movable on the frame by power means, toggle members connecting said depending arm and said actuating member and adapted to be extended substantially horizontally by said arm and approach straightened relation as the press is closed, and movable means associated with said actuating member and arranged to move into position for supporting said toggle members when moved to said extended relation, said actuating member being adapted to exert pressure upon said arm through said toggle members when so extended, to thereby effect pressure between said pressing members.

3. A pressing machine, comprising a frame, a pair of relatively movable pressing members mounted thereon, one of said members having a depending arm, an actuating member movable on the frame by power means, toggle members connecting said depending arm and said actuating member and adapted to be extended substantially horizontally by said arm and approach straightened relation as the press is closed, and movable means associated with said actuating member and arranged to move into position for supporting said toggle members when moved to said extended relation, said movable means including means for engaging said toggle members to complete straightening movement thereof, said actuating member being adapted to exert pressure upon said arm through said toggle members when so extended, to thereby effect pressure between said pressing members.

4. A pressing machine, comprising a frame, a pair of relatively movable pressing members mounted thereon, one of said members having a depending arm, an actuating member movable on said frame by power means, toggle members connecting said depending arm and said actuating member and adapted to be extended substantially horizontally by said arm and approach straightened relation as the press is closed, and a cam surfaced member movable into engagement with said toggle members when in said extended position and arranged to complete straightening movement thereof, said actuating member being adapted to exert pressure through said toggle members when so extended, to thereby effect pressure between said pressing members.

5. A pressing machine, comprising a frame, a pair of relatively movable pressing members mounted thereon, one of said members having a depending arm, an actuating member movable on said frame by power means, toggle members connecting said depending arm and said actuating member and adapted to be extended substantially hori-

zontally by said arm and approach straightened relation as the press is closed, and a cam surfaced member operatively related to said actuating member and movable into en-

5 gagement with said toggle members when in said extended position and arranged to complete straightening movement thereof, said actuating member being adapted to exert pressure through said toggle members when so extended, to thereby effect pressure between said pressing members.

6. A pressing machine, comprising a frame, a pair of relatively movable pressing members mounted thereon, one of said mem-

15 bers having a depending arm and a handle whereby the same may be closed upon the other member, an actuating member movable on said frame by power means, toggle members connecting said depending arm and said

20 actuating member and adapted to be extended substantially horizontally by said arm as the press is closed, movable means associated with said actuating member and arranged to move into position for supporting said

25 toggle members when moved to said extended position, said actuating member being adapted to exert pressure through said toggle members when so extended, to thereby effect pressure between said pressing members.

30 30 members, and a controlling handle for said power means widely spaced from said pressing member handle.

7. A pressing machine, comprising a frame, a pair of relatively movable pressing members mounted thereon, one of said mem-

35 bers having a depending arm, an actuating member movable on said frame by power means and having an extending arm, toggle members connecting said depending arm and

40 said extending arm and adapted to be extended substantially horizontally by said de-

pending arm as the press is closed, and mov-

able means operatively associated with said

actuating member and arranged to move into

position for supporting said toggle members 45 when in said extended relation, said actuating member being adapted to move the extending arm thereof into substantially straightened relation with said extended toggle members, to thereby effect pressure 50 between said pressing members.

8. A pressing machine, comprising a frame, a pair of relatively movable pressing members mounted thereon, one of said members having a depending arm, an actuating

55 member oscillatory on said frame by power means and having an extending arm, toggle members connecting said depending arm and said extending arm and adapted to be ex-

60 tended substantially horizontally by said de-

pending arm and approach straightened re-

65 lation as the press is closed, and a movable cam surfaced member in operative relation with said actuating member and arranged to engage said toggle members when in extended position and substantially complete straightening movement thereof, said actuating member being adapted to move the ex-

70 tendsing arm thereof into substantially straightened relation with said extended toggle members, to thereby effect pressure

75 between said pressing members.

9. A pressing machine, comprising a bed, a pressing head, an operating arm connected thereto, toggle members connected to said

75 arm and arranged to move toward extended position as the press closes, a movable toggle holding member mounted to move into en-

80 gagement with a knuckle of said toggle members when in extended position, and power means for operating said movable member and for applying pressure to said toggle members to transmit the same there-

85 through to the head.

In testimony whereof I hereby affix my signature.

DANA H. BENJAMIN.
